UNITED STATES PATENT OFFICE

A. B. BARLOW, OF RIPON, WISCONSIN.

IMPROVEMENT IN PUMPS.

Specification forming part of Letters Patent No. **58,972**, dated October 23, 1866.

To all whom it may concern:

Be it known that I, A. B. BARLOW, of Ripon, in the county of Fond du Lac and State of Wisconsin, have invented a new and useful Improvement in Double-Action Pumps; and I do hereby declare that the following is a full, clear, and exact description thereof, which will enable others skilled in the art to make and use the same, reference being had to the accompanying drawings, forming part of this specification, in which—

Figure 1 represents a vertical section of a pump made according to my invention, *y*, Fig. 2, being the line of section. Fig. 2 is an under side view of the pump's bottom, looking upward toward the section cut along the horizontal line *x* of Fig. 1.

Similar letters of reference indicate like parts.

The object of this invention is to obtain a pump which may be operated in deep wells, such as oil-wells, and in other places where it is desired to submerge the cylinder or the induction-pipe leading into it. The piston and piston-rod are hollow, the former being provided with a valve, while the liquid to be raised is admitted into the cylinder above the piston, and also below it, through independent valves.

M designates the cylinder of the pump. It has a valve, *G*, in its bottom, which is guided by vanes projecting radially from the valve-stem.

A designates the hollow piston-rod, opening into the chamber *B* of the piston through the opening *F*. The bottom of the piston has a valve-opening, *E*, and there is another valve-opening, *D*, at its top, at one side of the piston-rod. Both these openings are governed by the same valve *C*. This valve in this example is spherical, and is to be guided in any suitable manner so that it shall not obstruct the opening *E* of the piston-rod.

L is a side chamber, cast with the cylinder, and connected therewith at the top by an opening, *b*, which enters the upper part of the cylinder. This side chamber has a valve, *H*, at its bottom, of the same construction as the valve *G*.

The seats of the valves *G H* are made in a piece, *I*, which extends beneath the cylinder and the side chamber and forms the bottom for both of them.

The bottom piece *I* is supported and enclosed by an annular plate, *N*, surmounted by a flange, *N'*, whose upper edge meets the flanged edges of the chamber *L* and of the cylinder, their under sides being recessed in order to receive the bottom piece *I* and the packing *a*, and thereby form a tight joint to prevent leakage.

A packing, *a*, is placed on both sides of the said bottom piece *I*, and the lower or outer packing is held fast by means of the annular plate or cap *N*.

By the use of the separate bottom plate *I*, I am enabled to confine the packing *a* securely within surrounding flanges *N'*, which effectively prevent it bursting or pressing laterally outward, as it does when pressed between simple flat plates.

Both valves *G* and *H* open into a common chamber, *J*, which has a pipe, *K*, leading down into the liquid to be raised.

The annular plate or cap *N* is seen in bottom view in Fig. 2.

When the case of the chamber *J* is removed, the valves *G* and *H* are got at by simply removing the annular plate or cap *N* and bottom piece *I*, which, with the case of the chamber *J*, are held to the pump by the same bolts, thus greatly simplifying the construction of the apparatus.

In operating the pump the descent of the piston will cause the valve *G* to be closed. The valve *C* will be forced up to its seat to close the valve-opening *D*, when a partial vacuum will be formed in the upper part of the cylinder and in the said chamber *L*, causing the valve *H* to be opened by the pressure of the liquid in the well, and the liquid to run into said chamber *L*. When the valve ascends, the valve *C* will close the opening *E* in the bottom of the piston, and the valve *G* will be raised by reason of the partial vacuum formed in the lower part of the cylinder. The valve *H* will be closed by reason of the ascent of the piston, and the fluids and liquids in the upper part of the cylinder will be forced into the piston, whence it must go into the hollow piston-rod. A repetition of these operations will cause the fluids and liquids to ascend the hollow piston-rod to the place of discharge.

It will be observed that by reason of the closed chamber *J* and its pipe *K*, which latter

is extended downward into the liquid to be raised, the cylinder may be placed about thirty feet above the surface of the liquid in the well.

Moreover, the arrangement of the valves and the construction of the piston and its rod are such as to cause that the weight of the column of liquid in the piston-rod is only on that valve G and H which ought to be closed during the operations of the piston, whereby there is no reaction against the liquid or fluid in the well, nor against the incoming fluid as it enters the induction-valves G and H.

Having thus described my invention, I claim

as new, and desire to secure by Letters Patent—

The method, substantially as above described, of packing the lower joints of the cylinder and said chamber by means of a bottom piece, I, and annular flange or cap N and the packing material *a a*, secured by them by the aid of a surrounding flange, N', substantially as described.

A. B. BARLOW.
